UNITED STATES PATENT OFFICE.

JACOB E. PUTTER, OF ST. JOSEPH, MISSOURI.

ELECTRIC INCANDESCENT LAMP.

1,096,859.

Specification of Letters Patent. Patented May 19, 1914.

Application filed June 18, 1912. Serial No. 704,450.

To all whom it may concern:

Be it known that I, JACOB E. PUTTER, a citizen of the United States, residing at St. Joseph, in the county of Buchanan and State of Missouri, have invented certain new and useful Improvements in Electric Incandescent Lamps, of which the following is a specification.

This invention relates to an improvement in incandescent electric lights of the tungsten type.

The principal object of this invention is to so construct the light that the candle power will be greatly increased.

Another object is to so construct the light that the rays will be reflected from a series of lenses which are mathematically correct, thus insuring the light rays being reflected evenly all around the lamp.

In order to more fully describe my invention so that one skilled in the art can reproduce the device I refer to the following figures, which disclose the same.

Figure 1 is a side elevation of my lamp. Fig. 2 is a cross section of a modified form. Fig. 3 is a diagrammatical view showing how the light is reflected evenly around the same. Fig. 4 is a cross section taken on the line $\alpha-\alpha$ of Fig. 1. Figs. 5 and 6 show modified forms of reflectors.

Like numerals designate corresponding parts throughout the several views of the drawing.

The numeral 5 designates the usual lamp bulb attached to a plug 6. It is customary in tungsten lights to provide a support for the filament which is very fragile. This is usually a glass rod having wire supports sealed near the plug and near the extreme end. From these wires the tungsten filament is supported. In my lamp I replace this glass rod with a reflector.

I am aware that it is old to place reflectors within incandescent electric light bulbs but I do not believe that a reflector of the character I am about to describe has ever been used. The usual sealing in tube 7 is employed; to this is attached my reflector 8, the same has a multiplicity of sides which

are constructed upon a parabolic curve. 50 These curved faces are molded with mathematical accuracy. On the lower end of my reflector is a projection 9 which carries supporting rods 10. There are corresponding supporting rods 10' at the top and between 55 these the filament 11 is stretched but instead of running diagonally as in the ordinary lamp it is so wired that it runs vertically in parallelism with the reflector and at a predetermined distance therefrom. 60 This distance being the focus for the curved surface.

Referring to Fig. 2 I show a modified form of lamp which has a reflector formed integral with the globe proper. The reflector is merely a continuation of the bulb 5 turned back within itself at 12 so as to form the reflector 13. This reflector may have sides of varying number. The supports in this instance are in the form of 65 70 rings and are carried by both ends of the reflector 14 and 14' and filament 15 stretched between and so wired as to run vertically and in parallelism with the face of the reflector. The inside of the reflector 13 may 75 be either silvered or a silver tube may be placed within the cavity to cause the reflection.

Having described my invention what I claim is:—

1. An incandescent lamp comprising a vacuum bulb, a tubular member supported in the center of the bulb, and formed of uniform cross section and also formed with a plurality of reflecting surfaces, ring filament supports secured to the tubular member near its upper and lower ends, and a filament supported on the ring supports and having portions extending in parallelism with each of the reflecting surfaces and disposed medially thereof.

2. An article of manufacture consisting of a vacuum bulb having a tubular member formed on its lower end and extending inwardly toward the neck of the bulb, the upper end of said tubular member being closed and the bulb neck having an inwardly drawn sleeve surrounding the closed end of the

tubular member, said tubular member being shaped to provide a plurality of concave reflecting surfaces, and a filament supported on the tubular member and having its terminal portions extended through the neck between the sleeve and the closed end of the tubular member.

In testimony whereof I affix my signature in presence of two witnesses.

JACOB E. PUTTER.
